UNITED STATES PATENT OFFICE.

ELLIS C. SCHNEEBELI, EDWIN E. HELICK, AND MORRIS A. HALDEMAN, OF NAZARETH, PENNSYLVANIA, ASSIGNEES TO G. A. SCHNEEBELI & CO. INC., OF NAZARETH, PENNSYLVANIA, A CORPORATION OF PENNSYLVANIA.

LACE-DRYING MACHINE.

1,238,576.

Specification of Letters Patent. Patented Aug. 28, 1917.

Application filed February 17, 1915. Serial No. 8,780.

To all whom it may concern:

Be it known that we, ELLIS C. SCHNEEBELI, EDWIN E. HELICK, and MORRIS A. HALDEMAN, citizens of the United States, residing in Nazareth, Northampton county, Pennsylvania, have invented certain Improvements in Lace-Drying Machines, of which the following is a specification.

One object of our invention is to provide mechanism for quickly and efficiently drying fabrics and more particularly, for drying lace after it has been sized with starch solution; it being also desired that said mechanism shall be simple in construction and easy to operate.

These objects and other advantageous ends we attain as hereafter set forth reference being had to the accompanying drawings in which,

20 Fig. 1 is a perspective view illustrating the exterior of a drying machine constructed according to our invention;

Fig. 2 is a longitudinal section of the machine shown in Fig. 1;

25 Figs. 3 and 4 are sections taken respectively on the lines *a—a* and *b—b*, Fig. 2;

Fig. 5 is an enlarged section of the stretching mechanism which we employ;

Fig. 6 is a fragmentary perspective view 30 of the conveying means forming part of our invention; and

Fig. 7 is a fragmentary perspective view of a modified form of conveying means.

Referring to the drawings, 1 is a casing 35 forming an enclosure for a supporting frame 2 which has bearings 3 for two rotatable shafts 4, each having a sprocket wheel 5 fixed to it at one end and a sprocket wheel 6 splined to it adjacent its other end.

40 One of the shafts 4 has one of its ends extended through the casing 1 and provided with a sprocket 7 connected through a chain 8 with a sprocket 9 on a driving shaft 10 which is supported by brackets 11 secured 45 to the said casing.

The shaft 10 has a clutch collar 12 slidably keyed thereto and movable by clutch-shifting mechanism (not shown) into engagement with either of two clutch faces 13 and 14 on pulleys 15 and 16 respectively loosely mounted on said shaft and driven in opposite directions. By alternately moving the clutch member 12 into engagement with the clutch faces 13 and 14, the shaft 10 and consequently the sprocket 7 and its

shaft 4 will be rotated first in one direction and then in an opposite direction.

The sprockets 5—5 and 6—6 are respectively connected by conveying chains 17 and 18, the links of which have extensions 19 provided with substantially parallel pins 20. Said extensions 19 of the chain 17 also carry sleeves or pipes 21 into which extend the free ends of rods 22 similarly carried by the extensions 19 on the chain 18 (see Figs. 3 and 4). These sleeves 21 and rods 22 form a support for lace or other material to be dried and prevent it from falling between the conveying chains when it is detached from the pins 20.

As shown in Fig. 5 each pair of the sprockets 5 and 6 at the ends of the machine carries a series of rods 23 which are rotatably mounted therein but prevented from moving longitudinally by cotter pins 24 passing through them in engagement with washers 25. These rods each has an enlarged portion 26 providing a shoulder abutting the wheels 5 opposite the cotter pins 24 (Fig. 5), and their opposite ends are threaded at 27 for engagement with threaded sleeves 28 mounted in the wheels 6. Each of the rods 23 has fixed to it a sprocket 29 and a chain 30 passes around all the sprockets belonging to one pair of the wheels 5—6, so that if any one of said rods is turned all of the rods in that series will be turned to the same extent, thus sliding the corresponding wheel 6 on its shaft 4 toward or from the wheel 5.

To facilitate the turning of the rods 23 one end 31 of each of them is made square so that a wrench or hand lever may be applied.

A heating element which is illustrated as 95 a coil 32, is placed adjacent the bottom of the casing 1 directly below the bottom runs of the chains 17 and 18 and two air circulating fans 33 and 34 are secured to a vertical shaft 35 supported in bearings 36 and 37 on the frame 2 between the planes of the two chains 17 and 18. The blades of these fans are pitched in opposite directions so that when the shaft 35 is rotated the fan 33 will move the air upwardly while the fan 34 will move it downwardly. Said shaft has fixed to it a pulley 38 driven by a belt 39 passing over idler pulleys 40 around a pulley 41 on a shaft 42 and thence out through suitable openings in the casing 1 to 110

a driving motor. Said shaft 42 is supported from the top of the casing in bearings 43 and passes through an opening 44 into a take-off pipe or flue 45 where it carries a fan 46 designed to draw the air out of the interior of said casing.

The casing 1 has doors 47 at its opposite ends which may be opened in order to allow the operator to apply the lace to and remove it from the mechanism above described.

Under operating conditions the lace after it has been sized with starch solution or the like, is placed on the pins 20 of the chains 17 and 18 while the wheels 5 and 6 are rotating, being engaged thereby at points adjacent the edges. After all the lace has been run on the chains the machine is stopped and the rods 23 are adjusted to move the wheels 6 away from the wheels 5 until the lace is held at the proper tension by the resulting separation of the two sets of chains. The doors 47 are then closed and the clutch member 12 is thrown in so that the shafts 4 with their sprockets and lace supporting chains are turned at the proper speed and at the same time the fans are operated by the belt 39 which is driven from any desired source of power. Steam is supplied to the heating coil 32 and the air heated thereby will dry the lace, the fan 34 tending to drive the air through the bottom run of the lace while the fan 33 drives it through the upper run. The moisture laden air at the top of the casing is continuously taken off by the fan 46.

When the lace has been sufficiently dried the clutch member 12 is moved to its neutral position and after the rods 23 have been turned to move the wheel 6 toward the wheel 5 said lace may be easily removed from the pins 20, when it is ready for the market without further treatment.

While in Fig. 6 the conveying chains are shown as having open links they may be made of solid substantially rectangular blocks having upwardly projecting lace holding pins 20^a and be joined by pivot pins 48. When using this latter type of conveying chains each of the rods 22 may have one of its ends rigidly secured to a link on the chain 50 17 and its other end slidable through a link on the chain 18; thus doing away with the necessity for sleeves 21. In this case the rods 22 would extend the entire distance between the chains 17 and 18 and normally 55 have a portion extending beyond the latter so as to permit of an increase of the distance between said chains if desired.

The heating member 32 may be of any desirable construction and can be made of 60 coiled pipe when it is desired to use hot water, steam or hot air, though it may be made of plates or wire if the heating is to be done electrically.

We claim:—

65 1. The combination of a supporting

frame; two shafts journaled thereon; a sprocket fixed to each shaft; a sprocket slidably keyed to each shaft; a chain connecting the fixed sprockets; a second chain connecting the slideable sprockets; means on each of said chains for holding the material to be dried; means for sliding said latter sprockets on their respective shafts to increase or decrease the distance between the holding means of the chains; and means adjustably connecting said chains. 70 75

2. The combination of a supporting frame; two shafts journaled thereon; a sprocket fixed to each shaft; a sprocket slidably keyed to each shaft; a chain connecting the fixed sprockets; a second chain connecting the slideable sprockets; means on each of said chains for holding the material to be dried; means for sliding the latter sprockets on their respective shafts to 80 vary the distance between the holding means of the chains; said means including a set of concentric rods movably secured to each of the fixed sprockets and threaded into said slideable sprockets. 85 90

3. The combination of a supporting frame; two shafts rotatably mounted thereon; a sprocket fixed to each shaft; a second sprocket slidably keyed to each shaft; a conveying chain connecting said fixed sprockets; a second conveying chain connecting said slideable sprockets; a series of rods movably secured to each of said fixed sprockets and threaded into said slideable sprockets; with means for operatively connecting the rods of each series whereby movement of one of said rods will cause movement of the other rods of the same series. 100

4. The combination of a supporting frame; two shafts rotatably mounted thereon; a fixed and a slideable sprocket on each of said shafts; a conveying chain connecting the fixed sprockets; a second conveying chain connecting the slideable sprockets; telescoping members extending between said chains and supported thereby; means on the chains for holding material to be dried; means for moving the slideable structures relatively to the fixed structures; and means for driving one of said shafts. 110 115

5. The combination of a supporting frame; two shafts rotatably mounted thereon; a fixed and a slideable sprocket on each of said shafts; a conveying chain connecting the fixed sprockets; a second conveying chain connecting the slideable sprockets; a series of fabric supporting members connecting said two chains and constructed to permit of their movement toward and from each other; means on the chains for holding the material to be dried; a casing inclosing said mechanism; and means for heating said casing. 120 125

6. The combination of a supporting 130

frame; two shafts rotatably mounted thereon; a fixed and a slideable sprocket on each of said shafts; a conveying chain connecting the fixed sprockets; a second conveying chain connecting the slideable sprockets; members connecting said chains; means on said chains for holding the material to be dried; a casing inclosing said mechanism; and fans located between the runs of the conveying chains for circulating air through the material on said chains.

7. The combination of a supporting frame; two shafts rotatably mounted thereon; a fixed and a slideable sprocket on each of said shafts; a conveying chain connecting the fixed sprockets; a second conveying chain connecting the slideable

sprockets; members connecting said two chains; means on said chains for holding the material to be dried; a casing inclosing 20 said mechanism; fans located between the runs of the conveying chains for forcing air through the material on said chains; means for heating the casing; and means for exhausting the air from said casing. 25

In testimony whereof, we have signed our names to this specification, in the presence of two subscribing witnesses.
